UNITED STATES PATENT OFFICE.

JOHN EMANUEL JOHNSON AND CHARLES H. OSLUND, OF WORCESTER, MASSACHUSETTS, ASSIGNORS TO THE O. & J. MACHINE COMPANY, OF WORCESTER, MASSACHUSETTS, A CORPORATION OF MASSACHUSETTS.

MILK-BOTTLE CAP.

Application filed May 1, 1925. Serial No. 27,284.

This invention relates to a paper or similar cap for milk bottles particularly, but capable of other applications.

The principal objects of the invention are 5 to provide a milk bottle cap which can be sealed by a non-metallic seal which can be put on the cap and bottle by means of a labelling machine suitable for other purposes, thereby extending the use of labelling 10 machines; and also to provide a cap which will entirely seal the top of a bottle and will be firmly fixed in position by means of a paper or other similar band applied easily and rapidly and thus costing very little to 15 apply.

The invention incidentally involves the elimination of the wire sealing devices which are the cause of a good deal of trouble in this art, as is well known.

20 Other objects and advantages of the invention will appear hereinafter.

Reference is to be had to the accompanying drawings, in which

Fig. 1 is a side view of a milk bottle with 25 a cap thereon constructed in accordance with this invention;

Fig. 2 is a plan of a blank for the main part of the cap; and

Fig. 3 is a side view of the cap ready to be 30 applied.

The soft pasteboard milk bottle caps are now used extensively to cover the entire top of the bottle and prevent the entrance of dirt and moisture. They are held in position by 35 a soft wire surrounding the shank or neck of the cap and clamped by it to the neck of the bottle, this wire being made so as to be easily detached or loosened. Very often the wires

are only loosened in the household and re- 40 main on the bottle afterwards so that they require a certain amount of labor and time to remove them and they are also open to several other objections. This invention is designed to avoid those difficulties by the 45 substitution of a paper or similar band around the cap at the neck of the bottle.

These paper caps have usually been made of a circular sheet of soft pasteboard par- 50 affined to render them waterproof. If sold in flat shape they would have to be folded and creased around the neck which would leave them very rough and irregular. Therefore the circular edge is creased in the

factory in a neat and regular manner, which is a rather costly and difficult operation. On 55 account of these creases a simple paper band could not be pasted around them smoothly to hold the cap in position. This invention is designed to secure the above mentioned advantages and particularly to avoid these 60 folds so that the cap can be held down on the bottle smoothly and a band applied around the neck by an ordinary labelling machine and the expense of the creasing eliminated.

65 For this purpose we take a circular blank 10 of soft pasteboard or other suitable sheet material as has been done before, but we cut triangular notches 11 at regular intervals 70 around its circumference, leaving a series of tongues 12 projecting radially from it. These tongues all begin on a circle 13 which, when the cap is folded, as will appear, forms the edge of the cap proper at the largest circumference of the mouth of the bottle. The 75 tongues 12 at their bases occupy all the space around this circle 13 and consequently the sum of the distances across them equals the circumference of that circle. It is to be remembered that that circle is the largest 80 circle on the whole cap when in place. Therefore these tongues are tapered slightly so that their outer ends 14 are shorter than their bases along the circle 13 and they are made just wide enough so that the sum of 85 their widths constitutes the circumference of a smaller circle at the base of the mouth of the bottle. In other words, the sum of the widths of these tongues around the blank equals the circumference of the neck of the 90 bottle.

The edges from the bases of the tongues to their ends may be curved but preferably 95 are drawn on two straight lines intersecting each other along another circle 15. These two edges 16 and 17 make a slight angle with each other, the pairs of edges 16 converging and the pairs of edges 17 being substantially parallel for the same tongue. For this reason this circle 15 comes just at the top of 100 the neck of the bottle and for this reason the edges 17 on two adjacent tongues just come together when the tongues are folded down.

105 In the application of the device, of course, the blank is centered over the top of the

bottle and the circle 13 comes, as indicated in Fig. 1, along the part of the mouth which is of the greatest diameter and is just a little below the end of the mouth. The tongues 5 are brought down neatly over the converging under side of the mouth of the bottle so that the edges 16 just meet in a butt joint over that circle and the tongues are further smoothed down on the bottle neck and the 10 straight edges 17 come together in the same way along the substantially cylindrical neck of the bottle. Although described as parallel, these lines also converge slightly because this neck is usually slightly conical but this 15 makes a continuous surface around the neck of the bottle formed of the tongues 12 or rather the edges of the same which do not overlap or wrinkle but furnish a smooth surface.

20 Around this surface is placed a band 20. This is pasted around and overlaps a half inch or so, as is usual with labels. It is pasted by a labelling machine directly around the lower ends of the tongues 12 and 25 firmly seals the whole cap in position so that it is just as impermeable as a cap formed without the spaces between the tongues and is just as firmly fixed by the pasted band 20 as it would be by the wire and, in fact, more 30 firmly because it is held throughout the width of this band. This band may be formed of different grades of paper, even tissue paper and may be lined with a sheet of cheese cloth 21 to strengthen it; but in 35 any case it is employed to form a perfect seal around the bottle to hold the cap in position and prevent the entrance of dust or moisture. Preferably the cap is waterproofed by paraffine and the band may be 40 also but as its main function is to hold the cap and seal it, that is not essential.

This furnishes a sanitary seal which has all the advantages of the seals now on the market and the additional advantage that it 45 can be permanently secured and sealed by means of labelling machines, not especially constructed for this particular purpose, thus introducing important economy. We also

find an incidental advantage in the fact that on account of the fact that the bottle caps 50 can be cut out originally of the shape described without first cutting them in the form of circles and the fact that these tongues 12 can be formed in the notches 11 of the adjacent caps, there is a material economy 55 in the use of the material of these caps as an appreciably greater number can be made from a sheet of a given size.

Although we have illustrated and described only a single form of the invention, 60 we are aware of the fact that modifications can be made therein by any person skilled in the art without departing from the scope of the invention as expressed in the claims. Therefore we do not wish to be limited to 65 all the details of construction herein shown, or even to the system of machine banding, but what we do claim is:—

1. As an article of manufacture, a paper blank for a bottle seal of circular shape, having an unbroken circular center, and tongues radiating from said center and entirely surrounding it, said tongues having their edges converging slightly for about half their length and substantially parallel to the 75 rest of it, so that when applied to a bottle the edges of the tongues will practically come into contact throughout the length of the tongues.

2. A sanitary protective cap for the 80 mouths of bottles having an enlarged lip at the mouth and a constricted neck portion below said lip, said cap comprising a body portion adapted to overlie the mouth and a plurality of tabs each having an outer portion of uniform width adapted to enclose 85 said neck portion without overlapping and having a portion adjacent the body portion of uniformly varying width diverging from said first mentioned portion towards the 90 body portion adapted to enclose the lip.

In testimony whereof we have hereunto affixed our signatures.

JOHN EMANUEL JOHNSON.
CHARLES H. OSLUND.
